SEDIMENT SEPARATING AND GAS
LOCKING STOPPLE

Harry G. Moore, Los Angeles, Calif., assignor of
one-half to Edward L. Gonyer, Beverly Hills,
Calif.

Application February 20, 1935, Serial No. 7,389

6 Claims. (Cl. 210—57)

This invention is a stopple for containers of liquors, and more particularly is a device having a plurality of elements severally useable as sealing means for the container.

5 It is a purpose of the invention to provide means which will permit the final stages of fermentation of liquors, of alcoholic nature, to be carried on in the ultimate container; that is, the container from which the liquor will be dispensed by or to the consumer.

10 This is highly desirable since it preserves in the liquor its fermentation gases which, it is well known, are lost in the ordinary methods of making the liquor in large vessels and finally transferring it to the dispensing containers in which the liquor is sold or issued for consumption; the transfer being made after complete fermentation and clarification of the liquor.

An additional object is to provide a stopple 15 which is applied to the ultimate container after it has been filled with the partly fermented liquor, and then, after the stopple has been closed in the container to seal it, the container can be positioned for gradual settlement of the 20 usual sediment, from fermentation, on the lower area of the container wherein this stopple is applied, and, when the settlement has continued to the degree of desired clarity of the liquor, the sediment is removable by the stopple.

25 A feature of the invention is that the sediment may be removed from the cleared liquor without clouding it and without at any time admitting air to the liquor above the stopple device, and further without the loss of any of the trapped 30 fermentation gases in the container.

35 A further object is to provide a device of this character which is highly practical and effective, is substantial and durable, and parts of which may be repeatedly used in a filling plant, and in 40 which the part passing to the consumer with the container is of such small cost as to be negligible; especially when considered in relation to the much improved quality of the goods obtained by use of the device and enabling a better price 45 to be asked for the liquor.

The invention consists of certain advancements in this art as set forth in the ensuing disclosure and having, with the above, additional objects and advantages as hereinafter developed, and whose construction, combination and details 50 of means, and the manner of operation will be made manifest in the description of the herewith illustrated embodiment; it being understood that modifications, variations and adaptations may be 55 resorted to within the scope, principle and spirit

of the invention as it is more directly claimed hereinbelow. It is understood that the functional use of the apparatus of this disclosure in any other art than that herein set forth is deemed to be within the adaptation of the invention. 5

Figure 1 is a sectional elevation of an upright container sealed by the stopple just after filling with liquor.

Figure 2 is a sectional elevation of the container in the sediment settling position.

Figure 3 is a sectional elevation showing the remaining, sealing stopper in place after the settling stopper has been extracted.

Figure 4 is an elevation of the separated stem 15 and sealing bolt of the stopper.

It is understood that this stopple may be used on any desired form of container and that it is not limited for use on bottles 2 as here depicted. 20

It is preferred that the containers have a gradually contracted neck 3 and a mouth recessed at 4 for the seating of a washer 5 forming a part of the stopple.

The washer lies against the near end of a 25 stopper 6, which may be of any desired material, though an expandable material, as rubber or cork is preferred. Through the stopper 6 extends an axial stem part 7 of a shank 8 having a shoulder 8^a, and one end threaded at 8^b for an exterior 30 nut 9, and the other end internally threaded at 8^c to take a bolt 10.

This bolt passes through a second expandable stopper 11 and has a large head 10^a to support the stopper as this is axially compressed between 35 the head 10^a and a washer 12, on the opposite end of the stopper 11, when the bolt is screwed up tight as will be later described.

In a like manner the inner end of the stopper 6 is supported on a washer 6^a when the outside 40 nut 9 is screwed on tight to expand the upper stopper 6 in the neck of the container.

The assembled stopper, as just described, is adapted to be applied to the container after this 45 has been substantially filled with a liquor which has nearly completed fermentation; the stoppers being of a size to fit and be readily pressed into the neck 3, and the length of the unit, or stopple, being such that the stopper 11 will take a position clear of the neck surface while the upper 50 stopper 6 will stop at the top and the head washer 5 will rest in the neck recess 4.

When in place the upper stopper 6 is expanded by screwing up the jam nut 9 to a degree sufficient to hold the stopper 6 against possible blow- 55

out by the reasonably expected pressure incident to further fermentation of the sealed liquor.

The sealed container is now placed in an inverted position thus permitting the gradual settlement of the "ash" or sediment produced during the final fermentation of the liquor.

When fermentation is complete the sediment is found on the surface of the stopper 6 presented in the neck 3, and on the sides of the neck; the liquor now being clear and charged with the natural gases of fermentation.

For the purpose of removing the sediment the container is securely held (still inverted) with the least possible vibration, and a suitable tool 15 is applied to the stem end whereby the whole stopple unit is slowly pulled down until the inner stopper 11 comes into sealing contact with the converged neck wall; this occurring before the outer stopper 6 is clear of the neck mouth so 20 that no air may pass into the bottle neck during the change of position of the inner stopper 11. Continued pull is applied to the stopple until the inner stopper 11 is brought to its outer, full sealing position, as seen in Fig. 3. The stopper 25 11 is now supported against blow-out pressure by any suitable means.

Then the screw stem 8 is unscrewed, with the stopper 6 and washer 6^a, from the bolt 10; this being left in the stopper 11. A slotted washer 30 15 is now applied across the exposed bolt end and laid in the neck recess 3 and against the washer 12 and a nut 16 is run on the bolt end so as to expand the stopper 11 in the mouth of the neck to securely stand the probable gas pressure in the 35 container.

It will be seen that the sediment on the stopper 6 has been taken out with the stopper and that as the inner stopper 11 is drawn down it wipes the wall surface in the neck 3 and the 40 accumulated ash is washed out with the liquor caught between the two stoppers 6—11.

All of this operation is completed without loss of gas from the container and without admission of air, and the liquor is in its natural fermented state. No subsequent gas charging is required since the liquor has never been allowed to become flat.

What is claimed is:

1. Means to facilitate final fermentation of 50 liquor in its ultimate container, comprising a plurality of sealing stoppers fixed in spaced relation; the stoppers being so spaced that both occupy a sealing position at a portion of their

outward movement in the mouth of the container each stopper having means for its expansion in the mouth of the container to withstand expulsive pressure in the container.

2. Means to facilitate final fermentation of 5 liquor in its ultimate container, comprising a plurality of pressure sealing stoppers, and a connector fixing them in spaced relation; said connector being of sections capable of ready separation so that when the inner stopper is moved 10 to a sealing position in the container mouth the outer stopper may be entirely detached from the other stopper sealing the mouth.

3. Means to facilitate final fermentation of 15 liquor in its ultimate container, comprising a plurality of sealing stoppers fixed in spaced relation by a connector and movable as a unit, one stopper forming an outer seal in a container mouth while the other is positioned inwardly in the mouth to permit sediment settlement onto 20 the outer stopper whilst the container mouth is standing inverted; the inner stopper being shiftable by the connector to an outer sealing position as the outer stopper is drawn from sealing position and means for axially compressing and 25 laterally expanding the stoppers in their effective sealing positions to withstand expulsive pressure in the container.

4. A stopple comprising a pair of sealing stoppers, a separable section connector connecting 30 the stoppers, and means for axially compressing each stopper when it is disposed in a sealing position in a container mouth.

5. Means to draw sediment from the mouth of a container and to exclude air entrance and 35 prevent gas escape, and comprising a pair of sealing stoppers fixedly connected in spaced relation, one being disposed in sealing position in the mouth end and the other being disposed thereabove to allow sediment to fall to 40 the sealing stopper; the stoppers being connected by a device for movement as a unit to trap liquor between the stoppers and to drain it as the sealing stopper is extracted and as the inner stopper moves into full sealing position 45 in the mouth and means for severally expanding the stoppers in their effective sealing positions.

6. Means as set forth in claim 5, and in which the connecting device includes separable sections and means for severally expanding the stoppers in their effective sealing positions.

HARRY G. MOORE.
